METAL FRAME CONSTRUCTION

William C. Lyons, North Guilford, Conn.

Application December 29, 1950, Serial No. 203,311

6 Claims. (Cl. 189—46)

1

This invention relates to a metal frame construction and particularly a construction adapted for use in connection with cellar, bulkhead or hatchway doors. The invention is particularly concerned with the frame, usually rectangular in shape, which surrounds the opening closed by a door or doors, and which frame supports the door or doors in position.

The invention is illustrated as applied to cellar doors such as that shown in United States Letters Patent 2,174,989, granted October 3, 1939, to George W. Lyons, but it will be understood that the frame construction embodying the present improvements may be applied to other types of doors or closures.

In constructions of this type there is usually a frame, generally rectangular in shape, by which the doors are supported. It is desirable that this frame be made in parts so that it may be shipped in knocked-down condition or in disassembled condition, and the parts assembled when the door is installed. It is also desirable that these frames be weather-tight and, therefore, the joints between the various elements of the frame should be so constructed that when joined together, a substantially weather-tight joint will be effected.

Also, it is desirable that the frames be so constructed that even an inexperienced person may assemble them in correct relation, and this result is obtained in the present instance by so forming the elements of the frame that it is impossible to join them in any but the proper relation.

One object of the present invention is to provide a frame construction for hatchway, cellar or bulkhead openings which will be substantially weather-tight and which will comprise individual parts designed to be readily assembled together.

A still further object of the invention is to provide a frame construction of the character described which is so arranged that it is practically impossible to assemble the parts thereof in any but the proper relationship to each other.

A still further object of the invention is to provide a frame construction of the character described which consists of a number of individual parts, which parts are designed for convenient assembly by an inexperienced person to construct the completed frame.

To these and other ends the invention consists in the novel features and combinations of parts to be hereinafter described and claimed.

In the accompanying drawings:

Fig. 1 is a perspective view of a cellar door frame construction embodying my invention;

Fig. 2 is a perspective exploded view of the construction at one of the corners of the frame;

2

Fig. 3 is a view showing the parts of Fig. 2 in assembled relation;

Fig. 4 is a sectional view on line 4—4 of Fig. 3; and

5 Fig. 5 is a sectional view on line 5—5 of Fig. 3.

To illustrate a preferred embodiment of my invention, I have shown in the drawings a cellar door construction comprising a frame consisting of side members 10 of substantially triangular 10 shape. Adjacent the upper ends of these side members are rails or flanges 11 which may, if desired, be formed integrally with the side walls 10, and which flange extends in a plane at substantially right angles to the plane of the member 10.

Each of the flanges 11 is provided with an upwardly extending lip 12 along its inner edge, as shown more especially in Figs. 1 and 2, these lips cooperating with the peripheral downwardly-20 extending lips 13, provided at the edges of the doors 14 to make a weather-tight construction when the doors are closed.

The doors 14, as shown in Fig. 1, are hinged to the flanges 11 by hinges 15 so that they may be opened to a vertical position as shown. It will also be noted that, as shown in Fig. 2, the lip 12 does not extend throughout the length of the flange 11 but terminates at a point adjacent the upper edge of the corresponding door 14 so as to leave a portion 16 of the flange 11 with a flat edge unprovided with the upstanding lip.

A crosshead or header plate 17 is adapted to extend between the two flanges 11 at the top of the frame above the upper edges of the doors and 35 while no similar crosshead is shown at the opposite end of the frame, it will be understood that if a four-sided rectangular frame is desired, a similar crosshead may also be employed at the opposite end.

40 This crosshead consists generally of a flat plate of sheet metal, and when used in connection with cellar doors, as illustrated, may be provided with upwardly inclined lip 18 at its upper edge to fit against the wall of the building. This lip may or may not be provided depending upon the relation in which the frame is to be used. At its inner edge the metal of the crosshead is bent upwardly, as shown at 19, and then forwardly, as shown at 20, to overlie the body of the plate and create a channel to drain off the water falling

45 upon the crosshead 17. The downwardly-extending lip 21 at the top of the door is designed to lie above the edge of the member 20 so that the lower edge of the lip 21 will fit down relatively closely to the upper surface of the crosshead 17. 50 Adjacent each end of the crosshead is secured

by welding or the like a plate 23, the inner edge of this plate overlapping and being secured below the member 17, as shown at 24. This plate extends outwardly from the ends of the crosshead so that it may underlie the upper edge of the flange 11 and be secured thereto by the bolts 25. These bolts are passed through openings 26 in the plates 23 and registering openings 27 in the flanges 11, the assembled construction being shown in Fig. 3.

As shown in Fig. 2, the plate 23 at its inner end or at its end adjacent the door opening in the frame, extends inwardly beyond the crosshead or header plate 17 and beyond the upturned portion 19, as shown at 28. The inner edge of this extension 28 is turned upwardly to provide a lip 29 which abuts the member 19 and, as shown in Fig. 5, lies substantially parallel to, and spaced slightly from, the lip 12 on the flange. When the parts are assembled, as shown in Fig. 3, with the member 19 against the edge of the lip 12, the openings 26 and 27 will be in registration, the bolts 25 may be passed therethrough to secure the parts together. The edge of the flange 11 lies against the edge of the header plate but owing to the thickness of the material the edge of the lip 12 will abut against the part 19. Calking material 39 may be placed between the lips 12 and 29 so that rain cannot leak through the frame at this point.

In some instances it might occur that when the parts are assembled, a workman would place the flange 11 below the plate 23 instead of above this plate. This is impossible with the present construction, however, as the extension 28 of the plate 23, which extends beyond the plate 19, would engage the upper end portion of the lip 12 and prevent the assembly of the parts in this relation as the bolt openings 26 and 27 would not be in registration. It is only possible, therefore, to assemble the parts in the position shown with the upturned portion 19 of the header plate or crosshead abutting the end edge of the lip 12, as shown in Fig. 3, so that at this corner a tight joint will be made, particularly when the space 45 39 is filled with calking material.

I have described the construction at one end of the header plate 17, but it will be understood that the same construction will be employed at the other end of this plate, and that, if desired, a similar plate may be employed at the other end of the rectangular frame which would be connected with the side flanges 11 in the same manner. As illustrated, the parts of the frame are formed of sheet metal.

While I have shown and described a preferred embodiment of my invention, it will be understood that it is not to be limited to all of the details shown, but is capable of modification and variation within the spirit of the invention and within the scope of the claims.

What I claim is:

1. A frame construction comprising substantially parallel side members, a header plate extending between the ends of said side members to form a framed opening, each of said side members having an upturned lip along its inner edge, said lip terminating short of the end thereof adjacent the header plate, a plate member secured to the under-surface of the header plate at each end thereof and having a flat portion projecting from the edges of the latter, the inner edge of the header plate being bent upwardly, and means for assembling said members with the side members overlying the flat projecting portions of the

plate members and secured thereto, and the lip of each of the side members abutting the upwardly bent edge of the header plate, each of said plate members also projecting inwardly from the header plate to lie below the lip on the adjacent side member.

2. A frame construction comprising substantially parallel side members, a header plate extending between the ends of said side members to form a framed opening, each of said side members having an upturned lip along its inner edge, said lip terminating short of the end thereof adjacent the header plate, a plate member secured to the under-surface of the header plate at each end thereof and having a flat portion projecting from the edges of the latter, the inner edge of the header plate being bent upwardly, and means for assembling said members with the side members overlying the flat projecting portions of the plate members and secured thereto, the lip of each of the side members abutting the upwardly bent edge of the header plate, and said plate member also projecting inwardly from the header plate and having an upturned lip on said projecting portion lying adjacent the lip upon the adjacent side member and abutting the upwardly bent inner edge of the header plate, each of said plate members also projecting inwardly from the header plate to lie below the lip on the adjacent side member.

3. A frame construction as in claim 2 having calking material between the lip on the adjacent side member and the lip on the plate member.

4. A frame construction comprising a header plate having a plate member secured to its under-side adjacent each end thereof, said last-named plates having flat portions projecting from the ends of the header plate and also from one side thereof, a flat side member secured adjacent one of its ends to the upper surface of each of the plate members, the edge of each side member abutting the adjacent edge of the header plate, each of said side members having a lip extending to the edge of the header plate and overlying the flat portion of the adjacent plate member projecting from said side of the header plate, and the header plate having an upturned inner edge against which said lips abut.

5. A frame construction comprising a header plate having a plate member secured to its under-side adjacent each end thereof, said last-named plates having flat portions projecting from the ends of the header plate and also from one side thereof, a flat side member secured adjacent one of its ends to the upper surface of each of the plate members, the edge of each side member abutting the adjacent edge of the header plate, each of said side members having a lip extending to the edge of the header plate and overlying the flat portion of the adjacent plate member projecting from said side of the header plate, the header plate having an upturned inner edge against which said lips abut, and each of said plate members having an upturned lip spaced inwardly from, and substantially parallel to, the lip of the adjacent side member.

6. A frame construction comprising a header plate having a plate member secured to its under-side adjacent each end thereof, said last-named plates having flat portions projecting from the ends of the header plate and also from one side thereof, a flat side member secured adjacent one of its ends to the upper surface of each of the plate members, the edge of each side member abutting the adjacent edge of the header plate,

each of said side members having a lip extending to the edge of the header plate and overlying the flat portion of the adjacent plate member projecting from said side of the header plate, the header plate having an upturned inner edge against which said lips abut, and each of said plate members having an upturned lip spaced inwardly from, and substantially parallel to, the lip of the adjacent side member, and calking material between said lips.
